Attorneys.

UNITED STATES PATENT OFFICE.

CLYDE T. ELDREDGE, OF SAN FRANCISCO, CALIFORNIA.

MOTOR WAY.

Application filed June 29, 1922. Serial No. 571,602.

To all whom it may concern:

Be it known that I, CLYDE T. ELDREDGE, a citizen of the United States, and resident of San Francisco, county of San Francisco, 5 State of California, have invented a new and useful Motor Way, of which the following is a specification.

The present invention relates to improvement in road beds and has for its particular object the arrangement of the road bed in such a manner that it will accommodate the maximum amount of traffic. At present, heavy slow speed vehicles and light fast moving vehicles usually follow substantially 15 the same track with the resulting inconvenience, that very often the lighter vehicles capable of high speed are forced to run in the track of heavy slow moving vehicles with a resulting loss of time. Assuming, 20 for instance, that the traffic over a certain road comprises one heavy truck to ten fast moving automobiles, it will be seen that the latter are continuously hampered and retarded in their progress by the heavy trucks, 25 having to either adjust their speed to that of the trucks or being forced to try in some manner to pass around and to over-take the same. It is proposed to arrange special tracks in the road bed for the slow moving 30 vehicles and other tracks for the fast moving vehicles so that, for instance, all the traffic moving on the former tracks might be confined to a speed of say, ten miles an hour, while the traffic on the other tracks might 35 proceed at a speed of thirty miles per hour. In conjunction with this arrangement it is proposed to provide special means for reinforcing the different tracks in accordance 40 with their needs which allows of a comparatively light structure of the road bed as a whole. It is further proposed in a road bed constructed of concrete or similar material to provide suitable means allowing of expansion and contraction of the upper layer 45 which is particularly subjected to the influence of the changes in temperature.

With these and other objects in view the preferred form of the invention is shown in the accompanying drawing in which Figure (1) represents a top plan view of a road bed; Figure (2) a vertical cross section through the same; Figure (3) an enlarged vertical cross section through a portion of the same; Figure (4) a longitudinal cross 55 section through a portion of the same; Figure (5) a transverse cross section of a

slightly modified form and Figure (6) a top plan view of a single rail. While I have shown only the preferred forms of my invention I wish to have it understood 60 that various changes or modifications may be made within the scope of the claims hereto attached without departing from the spirit of the invention.

In its preferred form the road bed (1) 65 may be made of a comparatively thin layer of road bed material such as concrete. In the center portion of the road bed are provided two tracks (2) designed for heavy traffic. These tracks are preferably reinforced with suitable T beams (3) embedded in the road bed with underlying reinforcing strata (4) of concrete material which are preferably V shaped in cross section. The concrete and the T beams are connected 70 into one solid unit by means of transverse metal members (6) which latter again are secured to each other by means of longitudinal metal rods (7). To further reinforce that portion of the road bed underlying the T beams, I provide a plurality of metal rods (8) underneath the same with connecting members (9) securing them to the longitudinal rods (7) previously mentioned.

The T beams (2) serve not only the purpose of reinforcing the tracks but also of guiding the drivers of the vehicles and in case the reinforcing feature is deemed unnecessary, other suitable guide means may 90 be provided, as for instance, the longitudinal groove (11) shown in Figure 5.

The tracks for the heavy traffic are preferably disposed on each side of the center line 95 of the road bed so as to form the inner tracks while the tracks (12) for the lighter traffic are provided in parallel relation to the same near the border. The latter tracks are preferably constructed along the same principles with the only difference that lighter material may be used, the T beams (14) being lighter in weight and the reinforcing strata (16) of concrete being of smaller dimensions. To accommodate vehicles that for some reason or other, as for instance, 100 for repairing purposes, have to fall out of line, I provide a border (17) on each side, which may be of still lighter construction.

Concrete roads are frequently subject to cracking due to expansion and contraction 110 under the influence of the change in the temperature and I propose to eliminate this

cracking by providing longitudinal as well as transverse V shaped grooves (18), penetrating the upper layer of the road bed to which usually the influence of the heat is confined. These grooves may be filled with any suitable yielding material such as tar or the like. The longitudinal grooves may probably be omitted where the T beams are used since the joint between the concrete 10 and the T beams serves substantially the same purpose.

Where the grooves are used, it is advisable to reinforce the underlying concrete or other road bed material in a similar manner as heretofore described with reference to the rails as is shown at (20) in Figure (2) and the weakness caused by the transverse grooves may be compensated by reinforcing members (21) disposed below the same and laterally arranged reinforcing members (22) connected with the former by rods (23).

The tracks are preferably provided with antiskidding means such as the angular 25 grooves (19) arranged in parallel relation on the same.

I claim:

1. In a roadbed of comparatively light structure, a track for heavy traffic comprising rails embedded in the roadbed for guiding and reinforcing purposes, a reinforcement of the roadbed underneath each rail, longitudinal reinforcing rods running parallel to the rails in the plane thereof, longitudinal rods underneath the rails and transverse reinforcing rods connecting the longitudinal rods underneath the rails with the rods disposed in the plane of the rails. 30

2. In a roadbed of comparatively light structure, a track for heavy traffic comprising rails embedded in the roadbed having top flanges substantially flush with the level of the roadbed and bottom flanges buried within the roadbed, a reinforcement of the roadbed underneath each rail, longitudinal reinforcing rods running parallel to the rails in the plane thereof, longitudinal rods underneath the rails and transverse reinforcing rods connecting the longitudinal rods underneath the rails with the rods disposed 35 in the plane of the rails. 40

CLYDE T. ELDREDGE.
